(57) **CLAIM**

The ornamental design for a portable monitor, as shown and described.

DESCRIPTION

FIG. 1 is a front perspective view of a portable monitor showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another front perspective view of the portable monitor of FIGS. 1-7 shown in an open configuration of use; and,

FIG. 9 is another perspective view of the portable monitor of FIGS. 1-8 shown in another open configuration of use. Broken lines in the drawings depict portions of the portable monitor that form no part of the claimed design.

1 Claim, 9 Drawing Sheets
